UNITED STATES PATENT OFFICE

2,482,626

COMPRESSOR

Ralph E. Lamberton, Worthington, Ohio, assignor
to Joy Manufacturing Company, a corporation
of Pennsylvania

Application August 28, 1944, Serial No. 551,522

1 Claim. (Cl. 230—211)

1

My invention relates to compressor systems, and more particularly to improved means whereby cooling of the fluid after each of the stages of compression in a multi-stage compressor will be effected.

An object of my invention is to provide an improved compressor system. Another object is to provide an improved compressor having improved means for cooling the compressed fluid after each of the stages of compression in a multi-stage compressor. Still another object is to provide an improved heat exchange device adapted for use with a multi-stage compressor. Yet another object is to provide for a compressor having two low pressure cylinders and one high pressure cylinder, improved means for cooling the compressed fluid after it is discharged from each of the cylinders. These and other objects of my invention will be made more fully apparent in the course of the following description.

In the accompanying drawings, in which one illustrative embodiment of my invention is shown:

Fig. 1 is a plan view of a compressor having my improved cooling means associated therewith.

Fig. 2 is a front elevational view of the compressor shown in Fig. 1.

Fig. 3 is an enlarged vertical sectional view taken on the plane of the line 3—3 of Fig. 1.

Fig. 4 is an enlarged vertical sectional view taken on the plane of the line 4—4 of Fig. 3.

Fig. 5 is an enlarged horizontal sectional view taken on the line 5—5 of Fig. 3.

Fig. 6 is an enlarged horizontal sectional view taken on the line 6—6 of Fig. 3.

Fig. 7 is an enlarged sectional view of the head of one of the low pressure cylinders, taken on a plane including the axis of the cylinder and the longitudinal axis of the compressor.

There is shown in the illustrative embodiment of the invention a compressor, generally designated 1, having a pair of low pressure cylinders 2, and a high pressure cylinder 4 mounted on a crankcase 5. The low pressure cylinders are arranged in V relation with their axes lying in planes which are angularly related and are disposed at opposite sides of a vertical plane including the longitudinal axis of the compressor. The high pressure cylinder is arranged with its axis lying in the vertical plane including the longitudinal axis of the compressor. Enclosed in the crankcase is a crankshaft 7, and the usual transmission connections are provided between the crankshaft and the pistons contained within the cylinders. A suitable power or driving unit 9 is provided for driving the crankshaft.

2

Fluid to be compressed is taken into each of the low pressure cylinders 2, as shown in Fig. 7, from a conduit 11, through an intake passage 12 formed in a cylinder head 14, and past an inlet valve 15, during the suction stroke of the piston 16 in the cylinder. During the compression stroke of the piston, fluid is discharged from the cylinder past a discharge valve 18 and through a passage 19 formed in the cylinder head and leading to a discharge conduit 20. The cylinder head and the valve mechanism for each of the low pressure cylinders are the same, and since this structure per se does not enter into the invention, further description of the same is considered unnecessary.

Supported by the crankcase 5 at the side of the cylinders opposite the motor is a fluid cooling device 22 having intercooler sections 23 and 24, and aftercooler sections 25 arranged in planes extending transversely of the crankshaft. The 10 intercooler and aftercooler sections are similar in construction, and each includes upper and lower headers 26 and 27 having chambers 28 and 29 which are connected in communication with each other by tubes 30. Support members 31 are attached, as by welding, to the headers 26 and 27 at the sides of each of the intercooler and aftercooler sections, and radiating plates 32 spaced longitudinally of the tubes and extending transversely thereof, are fixed to the members 31 in 15 any suitable manner. The headers 26 and 27 are connected respectively, as by bolts 33, to transversely extending chamber providing members 34 and 35. The member 34 has chambers 36, 37, 38 and 39, the chambers 36 and 37 communicating with the chambers 28 of the intercooler sections 23 and 24 through ports 40 and 41 respectively, the chamber 38 communicating with one of the aftercooler sections through a port 42, and the chamber 39 communicating with another of the aftercooler sections through a port 43. The member 35 has chambers 45, 46 and 47, the chambers 45 and 46 communicating with the chambers 29 of the intercooler sections 23 and 24 through ports 48 and 49 respectively, and the 20 chamber 47 communicating with the aftercooler sections through ports 50.

The discharge conduit 20 for one of the low pressure cylinders is connected in communication with the chamber 45, and the discharge conduit 50 20 for the other low pressure cylinder communicates with the chamber 46. The chambers 36 and 37 are connected by conduits 52 and 53 extending longitudinally of the compressor between the high pressure cylinder and the low pressure cylinders at its opposite sides, to a common intake

conduit 54 for the high pressure cylinder. Fluid supplied to the high pressure cylinder through the conduit 54 is compressed and then discharged through a conduit 55 to the chamber 38. A conduit 56 connected in communication with the chamber 39 delivers the fluid after it has passed through the aftercooler sections, to a point of use or to a suitable receiver, not shown.

The crankcase 5 is provided with an end plate 58 which supports a bearing 59 for the end of the crankshaft adjacent the heat exchanger 22 and also supports a mounting 60 for a fan 62 which is driven by a pulley 64 attached to a reduced extension of the crankshaft. As the crankshaft is driven by the power unit 9, the fan operates to create an air stream which passes through the intercooler and aftercooler sections. The air stream engages the walls of the high pressure cylinder and is divided by the latter so that it flows through the spaces between the high and lower pressure cylinders, passing over the surfaces of each of the cylinders, over the fluid conducting conduits, and over the power unit 9.

Each of the low pressure cylinders 2 and the high pressure cylinder 4 is provided with an unloading device 66 to which an actuating fluid is supplied through a connection 68. The unloading devices are similar, and, as shown in Fig. 7, include a plunger 69 reciprocable in a bore 70 in the cylinder head and operative on the supply of fluid thereto for moving a rod-carrying element 71 in a direction to unseat the inlet valve.

During operation of the compressor, fluid is discharged from one of the low pressure cylinders to the lower ends of the intercooler sections 23 and flows upwardly through the latter to the chamber 36. Fluid discharged from the other low pressure cylinder enters the lower ends of the intercooler sections 24 and is conducted upwardly therethrough to the chamber 37. The conduits 52 and 53 carry the fluid from the chambers 36 and 37 respectively to the intake conduit 54 for the high pressure cylinder. Fluid delivered to the high pressure cylinder is compressed therein and then discharged through the conduit 55 to the chamber 38 where it passes to one of the aftercooler sections and is conducted downwardly to the chamber 41. The compressed fluid flows from the chamber 41 to another of the aftercooler sections which conducts it upwardly to the chamber 39 where it passes to the conduit 56 leading to a point of use or to a receiver. The air stream passing through the intercooler and aftercooler sections, and over the cylinder walls and the fluid conducting conduits produces an effective cooling of the compressed fluid.

As a result of my invention there is provided an improved compressor system having improved means for cooling the compressed fluid as it passes through the various stages of compression. It will be noted that the arrangement of the sections of the cooling means makes it possible to provide well arranged connections to the cylinders, and these connections are subjected to the cooling effects of the air stream passing through the cooling sections.

While there is in this application specifically described one form which the invention may assume in practice, it will be understood that this form of the same is shown for purposes of illus-

tration, and that the invention may be modified and embodied in various other forms without departing from its spirit or the scope of the appended claim.

What I claim as new and desire to secure by Letters Patent is:

In a compressor, in combination, a pair of low pressure cylinders supported in V relation, a high pressure cylinder arranged vertically between said low pressure cylinders with the longitudinal axis of the high pressure cylinder bisecting the V between the low pressure cylinders, a combined intercooler and aftercooler comprising radiator cross members in spaced relation and each having chambers therein, each of said cross members having two end chambers, the end chambers in one of said cross members arranged opposite the end chambers in the other cross member, and one of said cross members having two intermediate chambers between the end chambers therein and the other of said cross members having a single intermediate chamber opposite the last mentioned chambers in said one member, separate discharge flow connections leading from said low pressure cylinders respectively to said two end chambers of said other cross member, separate flow connections leading from said two end chambers of said one cross member to said high pressure cylinder, a discharge flow connection leading from said high pressure cylinder to one of said intermediate chambers of said one cross member, a terminal flow connection leading from said other intermediate chamber in said one cross member, said combined intercooler and aftercooler including parallel radiator sections connected between said cross members including radiator sections connecting the opposite end chambers in communication with each other and through which fluid flows from the chambers of said other cross member to said chambers of said one cross member and radiator sections severally connecting each of said two intermediate chambers to said single intermediate chamber, said cross members, flow connections and said radiator sections being so arranged and constructed that fluid may flow from one of said two intermediate chambers through one radiator section to said single intermediate chamber and from the latter in the opposite direction through another radiator section to said other of said intermediate chambers.
